AUTOMOTIVE VEHICLE ANTENNA

Joseph Benjamin Cejka, Highland Park, N. J., assignor to L. S. Brach Mfg. Corp., Newark, N. J.

Application May 25, 1948, Serial No. 29,065

13 Claims (Cl. 250—33)

1

This invention relates to an antenna construction especially adapted for mounting on some part of an automotive vehicle such as the cowl or fender. It has been found in practice that an antenna for an automotive vehicle should have a mounting such that the electrical signal losses will be held to a minimum.

It is therefore one of the objects of my present invention to provide an antenna for automotive vehicle use in which the Q or "dissipation constant" is held at the most favorable point. In order to attain this object several improvements have been found necessary. One of these is to get a water seal at the place where the antenna is mounted on the vehicle. This has always been difficult to attain during damp wet weather for if the insulation, which is a very important factor, at any place in the installation gets damp, leakage becomes excessive.

A further improvement resides in the reduction of the number of parts and simplification in manufacture. Another important improvement resides in the means for mounting the antenna on parts of a vehicle having different shapes. Other advantages or improvements, pointed out more in detail later, are found in the interior construction of the antenna sections whereby more uniform contact is obtained and noise is eliminated due to vibration in the vehicle and in the sections themselves and smoother action is obtained in the raising and lowering of the antenna.

These and other objects and advantages will be seen from a study of the following specification and annexed drawing wherein:

Figure 1 is a part sectional and elevational view of the complete antenna and its method of mounting.

Figure 2 is a view of the top section of the antenna on an enlarged scale from Figure 1.

Figure 2A is a section on the line 2A—2A of Figure 2.

Figure 3 is a part sectional and elevational view on an enlarged scale from Figure 1 of the section below the top section of Figure 2.

Figure 4 is a view similar to Figure 3 on an enlarged scale from Figure 1 but of the bottom or basic section.

Figure 5 is a view from the lower end of Figure 2.

Figure 6 is a view on the line 6—6 of Figure 4.

Figure 7 is a plan view of two inter-fitting sealing devices, the upper half of the figure showing the position of half of the top device while the lower half shows the upper half of the device turned 180 degrees.

Figure 8 is a side view of the sealing devices in one position separate from the antenna.

Figure 9 is a side view of the sealing devices in another position separate from the antenna.

2

Figure 10 is a sectional view on the line 10—10 of Figure 1.

In the various views wherein like numbers refer to corresponding parts 1 is a tubular housing for the basic or lower section 2 of the antenna. A clamp 3 is utilized for anchoring the lower end of the housing member 1 to some part of the vehicle body. The lower end of the housing 1 has a stop 4 of insulating material to limit the downward movement of the section 2, the lower end of which has guide members of insulating material which may be in the form of pins 5 and 5' at right angles to each other to balance the end or a washer may be forced over the end of the section. Fastened to the top of housing 1 is a metal collar 6 that is mounted on the lower end of an insulator 7. The collar 6 has an outwardly turned flange 8 on which rests an outwardly extending flange 9 of the insulator 7. The insulator 7 has an internal annular rib 10 fitting in a groove 11 in a metallic sleeve 12 which passes through the insulator 7 which is generally cylindrical in form. A lock ring 51 is forced over the sleeve 12 between it and the insulator 7 to hold them in permanent position, also a self thread cutting screw 52 is passed through a hole in the housing 1 into the collar 6. Encompassing the insulator 7 is a metallic member 13 having an inturned edge 14 which passes below the flange 8 of the collar 6. Preferably a gasket 15 is used at this junction with the end of 1 to seal the union. The member 13 has its top part formed conically to fit into a hole 16 in some part of the vehicle body and its outer surface may be roughened or provided with ribs 17 so as to grip into the wall of the hole 16.

For sealing off the hole 16 around the member 13 there is utilized a gasket 18 of flexible insulating material such as rubber, which has a rim 19 preferably inclined inwardly. Adapted to fit within the rim 19 is the edge of one face of a member 20, the opposite face of which has an annular shoulder 21 spaced inwardly from the face edge. Fitting on this face and around the shoulder 21 is another member 22. Both members 20 and 22 are of tough rigid insulating material and each has a narrow rim on one side of an axial plane and a much wider rim on their opposite sides, for example take member 20, the rim at 23 is narrow while at 24 it is much wider. Stated in another way the two washerlike members 20 and 22 when assembled as shown in Figures 1 and 8 have their engaging faces one with the other in a plane which makes an acute angle with the vertical axis of the antenna. By reason of this construction the washers 20 and 22 will by turning, accommodate themselves to any contour or slope of the body 25.

To hold the washers 20 and 22 in place, a flat washer 26 is used and a metallic nut 27 and a nut 28 of insulating material are threaded onto the

upper end of the sleeve 12. While the insulator 7 and sleeve 12 and member 13 are shown as separate pieces, the insulator 7 may be moulded in conjunction with 12 and 13 to make one piece in which case the outer surface of the sleeve 12 is knurled as at 55 to lock the moulded material thereto. It will be noted that the upper ends of the basic section 2 has positioned therein a pair of metallic washers 29 and 30 between which is positioned a leather washer 31 which engages the next section above as shown in Figure 3 to give a smooth running fit. Below the washers 29, 30, 31 there is located a short resilient sleeve 32 of Phosphor bronze preferably split and provided with one or more fingers 33 which engage the next section 39 above to make electrical contact therewith and to prevent rattle.

Likewise the next section above may be similarly constructed but as shown the leather washer 35 having an inside diameter of .090" is between a top metal washer 34 having an inside diameter of 104" and a metal sleeve 36 which is adapted to be engaged by springs 37 and 38 fastened as by welding to a flat surface 50 on the top section 40 which has the round metal flattened at 41 to provide a stop so this section cannot be pulled out of section 39. It will be noted that the top ends of sections 2 and 39 are spun over to co-operate with the stops on the co-action section. The lower end of section 39 is slotted at 53 to give a spring engaging action with section 2 within which it runs so as to hold the section in any adjusted position. The section 39 also has indentations 54 to act as stops for section 40.

In order to make circuit connection with the antenna a cable C is provided with a plug P to go into a receiver. A metallic sleeve 42 having having a flange 43 is fastened as by soldering to the housing 4 and the inner conductor 44 and its insulation passed through the sleeve 42, while the bared end is spot welded or soldered at 45 to the metal sleeve 12. The outer conductor 46 shown as braided wire is soldered at 47 to the sleeve 42 thereby giving a ground connection to the cable. Positioned over the outer insulation 48 of the cable B and over the end of the outer conductor there is insulation material 49.

It should be noted that the bottom slotted end of section 39 gives an outwardly acting pressure while the parts 34, 35 and 36 at the top produce an inwardly acting pressure, the advantage of which is that the tubular section 39 is held concentrically with respect to its associates and thereby insures double electrical contacts under vibration from the upper and lower sections.

From the construction and assembly as described it will be seen that I have provided an antenna that fulfills all the advantages or improvements specified.

Having thus described my invention, what I claim is:

1. An automotive vehicle antenna comprising a plurality of telescopic sections made up of a basic section, a top section and at least one intermediate section, a tubular member for housing the basic section but insulated therefrom, a metallic sleeve fitting over the upper end of the basic section and in electrical contact therewith a generally cylindrically shaped insulator fastened to the sleeve intermediate its ends, a metallic collar fixed to the insulator near one end for receiving the upper end of said housing member which is fastened thereto, a circular metallic member embracing the insulator adjacent

said collar and having its end away from the collar terminating in a conical surface to fit into a hole in some part of the vehicle body such as the cowl or a fender, means for sealing said hole including a circular gasket of flexible insulating material having preferably on one side a positioning rim and a pair of circular insulators of the washer type, one having a face surface to fit within the rim of said gasket and an opposite face with an annular shoulder, while the other of said pair has a surface on one face to fit the face around the annular shoulder of the first mentioned pair, these two interconnecting faces being in a plane forming an acute angle to the axis of the antenna sections, means including an insulator nut threaded to said sleeve for holding said gasket and pair of insulators in sealing position against the wall of said hole and means for making an electrical connection through the housing member to said sleeve.

2. An automotive vehicle antenna comprising a plurality of telescopic sections made up of a basic section, a top section and at least one intermediate section, a tubular member for housing the basic section but insulated therefrom, a metallic sleeve fitting over the upper end of the basic section and in electrical contact therewith a generally cylindrically shaped insulator fastened to the sleeve intermediate its ends, means for anchoring the sleeve and the said insulator to the upper end of said tubular member, means for making an electrical connection through the upper end of the housing member to the sleeve, a circular member embracing the insulator intermediate its ends and having a conical surface at its end farthest from the housing member, said conical surface being adapted to fit into the hole in the vehicle body, means for sealing said hole around said conical surface, comprising a gasket of flexible material for engaging the said body material around the hole, a pair of circular washer type parts fitting together on a plane making an acute angle to the longitudinal axis of the antenna, one of said washer parts having a face to fit said gasket while the other part has its outer surface or rim in a plane at right angles to the axis of the antenna, an insulating gasket to fit said rim and means including an insulator nut threaded to said metallic sleeve for holding said gaskets and washer type parts in sealing position.

3. An automotive vehicle antenna as set forth in claim 2 further characterized in that the top antenna section has two flat surfaces at its inner end with arcuately formed springs fastened at one end to said surfaces and having their free ends engaging opposite parts of said section which has its metal just above the free ends of said springs flattened or expanded to provide a pullout stop in association with an inwardly spun end of the section within which it fits.

4. An automotive vehicle antenna as set forth in claim 2 further characterized in that the union at least between the basic section and its associate includes at the spun over end of the basic section a pair of rings of suitable metal with an intermediate washer preferably of leather for contacting with the associate section and a split contact metal sleeve located adjacent said rings and having inwardly projecting resilient fingers for contacting with the associate section.

5. An automotive vehicle antenna as set forth in claim 2 further characterized in that said means for making said electrical connections include a metallic sleeve extending a substantial

distance away from the housing member near its upper end and having a flange for engaging the interior wall of the housing member and anchored thereto, the inner conductor of the antenna cable and its insulation located within said flanged sleeve and extending beyond the flange while the conductor with at least part of its parent insulation extends to and is fastened to the metallic sleeve carried on the basic section, the outer conductor of the cable extending over the metallic sleeve and being fastened thereto close to the housing member and an insulator extending from the housing member over the outer conductor and its outer insulation.

6. An automotive vehicle antenna as set forth in claim 2 further characterized in that said circular member with the conical surface has means on its outer surface to aid in making a secure holding engagement with the body portion of the vehicle at the hole.

7. An automotive vehicle antenna comprising a plurality of telescopic sections made up of a basic section, a top section and at least one intermediate section, a tubular member for housing the basic section but insulated therefrom, means for fastening the antenna to some portion of the vehicle body having a hole therein, said means including a metallic sleeve fastened to the basic section and having a connection to a conductor going to a radio set on the vehicle, an insulator carried by the sleeve, a metallic member embracing the insulator and locked thereto and having a conically shaped end to fit in said hole, a pair of washers of suitable rigid insulation having inter-engaging formations, so when they are together a continuous sloping surface is formed, each washer having a narrow rim on one side of an axial plane while the rim increases in width opposite to the narrow portions whereby the washers can take up positions throughout varying slopes of the vehicle body at the hole, a gasket of flexible insulating material next to the body material and means including an inner metallic nut and an outer one of insulating material screw threaded to said metallic sleeve for locking said washers and gasket securely to the material around the body hole.

8. An automotive vehicle antenna comprising a plurality of telescopic sections made up of a basic section, a top section and at least one intermediate section, a tubular member for housing the basic section but insulated therefrom, means for fastening the antenna to some portion of the vehicle body having a hole therein, said means including a metallic sleeve fastened to the basic section and having a connection to a conductor going to a radio set on the vehicle and further means including an insulator fastened to the sleeve with part of said last mentioned means having a conical surface to fit in said hole, a pair of washers of suitable insulating material having inter-engaging surfaces meeting in a plane making an acute angle with the axis of the antenna, a gasket of flexible insulating material next to the body material and means screw threaded onto the metallic sleeve for locking said washers and gaskets securely to the material around the body hole.

9. An automotive vehicle antenna for mounting in a hole in the vehicle body comprising a plurality of telescopic sections made up of a basic section, a top section and at least one intermediate section, a tubular member for housing

the basic section, means for insulating said basic section from said housing member, a metallic member carried by said insulating means and having a spherical surface to set into said hole and engage its peripheral wall, sealing means positioned on the body surface over the hole and around said spherical surface and means carried by said insulator for clamping said sealing means in position.

10. An automotive vehicle antenna as set forth in claim 9 further characterized in that the said spherical surface is roughened to bite into the wall of the hole to get a good grounding contact with the car body.

11. An automotive vehicle antenna as set forth in claim 9 further characterized in that the sealing means includes a pair of insulators having interacting shapes that will conform to various curvatures of the vehicle body where the hole is located, the insulator which directly contacts the car body being recessed to fit around that part of the spherical surface which protrudes through the hole.

12. An automotive vehicle antenna comprising a plurality of telescopic sections made up of a basic section, a top section and at least one intermediate section with means for insulatingly supporting the basic section, the basic section having at its upper end a pair of metallic washers between which is located a washer having the characteristics of leather and below said washers a sleeve of resilient metallic material having a plurality of integral fingers arcuately positioned around the sleeve to engage the next section above, while the section next above the basic section has its lower end slotted for exerting an outwardly acting pressure and at its top end means for exerting an inwardly acting pressure, said last mentioned means comprising a metallic sleeve against the upper end of which rests a washer having leather characteristics and held in place by a metal washer and the spun over end of the section, the washer with the leather characteristics having a much smaller hole than the metal washer.

13. An automotive vehicle antenna for mounting in a hole in the vehicle body comprising a plurality of telescopic sections made up of a basic section, a top section and at least one intermediate section, a tubular member for housing the basic section, means for insulating said basic section from said housing member, a unitary structure for supporting the antenna including, an insulator, a metallic sleeve carried within the interior of the insulator, a metallic member carried on the exterior of the insulator and having a conically shaped end to fit into said hole, insulating sealing means for fitting over the hole and protruding end of said metallic member and means carried by the upper end of said sleeve for holding said sealing means and the antenna to the vehicle body.

JOSEPH BENJAMIN CEJKA.
